UNITED STATES PATENT OFFICE.

PERLEY L. KIMBALL, OF BELLOW'S FALLS, VERMONT, ASSIGNOR TO VERMONT FARM MACHINE COMPANY, OF BELLOW'S FALLS, VERMONT, A CORPORATION OF VERMONT.

CENTRIFUGAL CREAM-SEPARATOR.

No. 920,481.

Specification of Letters Patent.

Patented May 4, 1909.

Application filed January 5, 1909. Serial No. 470,818.

To all whom it may concern:

Be it known that I, PERLEY L. KIMBALL, a citizen of the United States of America, residing at Bellows Falls, in the county of 5 Windham and State of Vermont, have invented certain Improvements in Centrifugal Cream-Separators, of which the following is a specification.

This invention relates to centrifugal cream-separators and consists in the improved construction of the means by which the series of separable superposed liquid subdividers within the bowl are definitely assembled, adjusted and retained in concentricity, and all held 10 together in a stable unitary structure independently of the bowl or other parts of the separator, so that it may be removed from the bowl and inserted therein as such structure, and when removed the component 15 parts may readily be released and separated for cleaning or repairing.

The detailed construction is set forth in the description following, in connection with the accompanying drawings, wherein—

Figure 1 is a vertical, diametrical section of the bowl with the series of superposed subdividers and their adjusting and retaining devices assembled therein; Fig. 2, a plan of the top plate of the series; Fig. 3 is a plan 20 of one of the intermediate subdividers of the series; Fig. 4 is an elevation of the lowest subdivider with two retaining rods; Fig. 5 is a detail of a portion of the upper plate showing in vertical section one of the rod-securing nuts with a tubular extension thereon; Fig. 6 is cross-sections on line 6—6 of the two retaining rods illustrated in Fig. 4.

Designating the several parts of the apparatus illustrated in the drawings by reference 25 letters; B is the bowl; S, the subdividers; s' the top plate and s² the lower plate of the series.

R are the adjusting and retaining rods for the subdividers, one of which, R', may be 30 made different in cross-section from any of the others for the purpose of definitely determining the relative circumferential position of the several subdividers by means of a notch in each having a shape corresponding 35 to that of the cross-section of the rod. This difference in cross-section of the rods also constitutes an unsymmetrical arrangement 40 of their peripheries, and the same result may be obtained by locating rods of similar cross-section unsymmetrically, either circumferen-

tially or radially, in respect to the axis of the bowl. Only two such rods are shown, but any other convenient number may be employed, and all may be permanently secured to the lower plate s² at p, and to the upper 45 plate s' by nuts N, which may be readily attached to and released from the screw-threaded portions t at the upper ends of the rods. When the series of subdividers are properly assembled about the rods R and 50 securely held by the nuts N, they become a stable unitary structure independent of any support from the bowl, and can be inserted therein and removed therefrom without any liability of disarrangement or separation; 55 and at the same time when this composite structure is removed, the parts may be readily separated by unscrewing the nuts from the rods.

C is the cover which fits into an annular 60 rabbet in the top of the bowl where a packing ring is inserted, and this cover is held firmly in place by a rod D provided with a collar e to rest upon the top of the cover, which rod extends down through the annular 65 openings in the subdividers and is screwed into a socket f in the bottom of the bowl. A cream outlet G is provided in the cover, and in order that it may always be located in the same position in relation to the top plate s', 70 an upwardly projecting stud H is secured upon that plate and a socket for the stud is formed in the under side of the cover. Skim-milk outlets I are made in the bottom of the 75 bowl, and to provide a passage for the skim-milk to those outlets between the bottom of the bowl and the lower plate s², short projections M are provided on the under side of 80 that plate.

The several subdividers herein illustrated 85 are constructed substantially like those shown in my prior patent No. 806,346 of December 5, 1905, having a flat annular perforated plate k, upon both sides of which a series of curved blades are secured, and 90 when the subdividers are superposed the opposed blades will interlock.

In the internal periphery of the annular plate of each subdivider, notches L are 95 formed, corresponding in location to that of the several rods R, R', in relation to the axis 100 of the bowl, and in shape to that of the cross-section of the respective rods; thus when the subdividers are being assembled the position 105 of each in relation to the others can readily 110

be determined by a glance at the inner circle of the annulus, the location and shape of the notches being an accurate guide to their location upon the rods R. One rod R' is shown 5 as rectangular in cross-section; but any other form which may be readily distinguished from the other rod will serve the purpose. Also, as the several subdividers are properly fitted, each to the others next 10 adjoining, in regular sequence, so that they will accurately interlock, it is desirable that the series should always be assembled in the same order in which they were originally fitted, and to insure this, each annular plate 15 is provided with a small projection w beyond the circle of its internal periphery, and upon the upper side of this projection a number, or other designating ordinal, is placed, which will indicate the vertical position of each 20 subdivider in relation to the others of the series. For practical results two of these adjusting and retaining rods R for the subdividers are found sufficient, but as previously stated more may be used if desired. 25 The two rods will, when the corresponding notches of the subdivider plates are placed over them, insure the concentricity of the whole series, and retain them in such position. The nuts N are of novel construction 30 and very convenient in this connection. Each nut is provided with a tubular extension o which loosely fits in a hole in the upper plate s'. The lower ends of these tubular extensions are flared outward at q and serve a 35 double purpose, first, the flaring lip prevents the nut from being accidentally removed from its socket in the plate and being mislaid or lost, and second, the flaring open end of the tube makes it very easy to find the 40 upper end of the rods R when the upper plate s' is placed upon the top of the series of subdividers; in fact, the operation is substantially automatic, for when the upper plate is placed in proper position upon the top of the 45 series, the tubular extensions of the nuts of necessity slide over the ends of the retaining rods.

As illustrated, the screw-threaded portion t' of the upper end of the rod R' is smaller 50 than that of the other rod, to serve as a means to indicate the proper circumferential position for the plate s' in relation to the series; but as previously stated, the location of one rod at a greater radial distance from 55 the axis of the bowl, or at a position other than diametrical in relation to the other, will serve as an indication for the same purpose.

To insure the rotation of the stack of subdividers with the bowl, a longitudinal rib u 60 is secured upon the interior of the bowl, and a corresponding groove v is formed in the outer periphery of each subdivider to slide over and engage the rib u when the series of subdividers are inserted within the bowl.

65 I claim:—

1. In a centrifugal cream-separator, provided with a series of superposed detachable annular subdividers within the bowl, a plurality of adjusting and retaining rods for such subdividers, which rods are secured to a 70 plate at the bottom of the series of subdividers and extend to a plate at the top of the series, one at least of which rods differs in cross-section from that of any other, notches at the inner margin of each annular subdivider to engage a plurality of such rods, and readily-released means to secure the upper ends of the rods to the upper plate.

2. In a centrifugal cream-separator, a series of superposed annular subdividers within 80 the bowl, a plurality of rods secured at one end to the lowest subdivider and extending upward within the annular openings thereof to the top of the series, one at least of which rods is unsymmetrically constituted in comparison with the others, as a means to indicate the relative circumferential positions of the subdividers, and readily-released means to secure the upper ends of the rods above 85 the series of subdividers.

3. In a centrifugal cream-separator, provided with a series of superposed annular subdividers within the bowl, a plurality of adjusting and retaining rods for such subdividers, one at least of which rods differs in 95 cross-section from that of any other, and all secured to a transverse plate at the base of the series of subdividers and extended to a plate at the top of the series, which rods engage the said subdividers, a screw-threaded portion at the upper end of each rod, one at least of such portions differing in diameter from that of any other, and nuts to engage and hold the ends of the respective rods.

4. In a centrifugal cream-separator, a series of superposed annular subdividers within 105 the bowl, a plurality of rods secured at one end to the lowest subdivider and extending upward in the annular openings thereof to the top of the series, to adjust and hold the 110 subdividers in concentricity, and a nut for each rod, which nut is provided with a tubular extension loosely socketed in a plate at the top of the series.

5. In a centrifugal cream-separator, a series of superposed annular subdividers within 115 the bowl, a plurality of rods secured at one end to the lowest subdivider and extending upward within their annular openings to the top of the series, to adjust and hold the subdividers in concentricity, a nut for each rod, which nut is provided with a tubular extension loosely socketed in a plate at the top of the series, and means to prevent the accidental removal of such nuts from their 120 sockets.

6. In a centrifugal cream-separator, a series of superposed and detachable annular subdividers within the bowl, a retaining plate above and another beneath the series. 125

a plurality of rods extending through the annular openings of the series of subdividers and adapted to be secured to the retaining plates independently of any milk-tube, which rods engage and adjust the subdividers in concentricity, and means to secure the rods to the plates so as to hold the assembled portions as a stable unitary structure indepen-

ently of other parts of the apparatus, and readily to release such portions for separation and cleaning. 10
